FOLDING CARD TABLE WITH LOCK MEANS

Cornell Flagstad, Minneapolis, Minn.

Application October 24, 1947, Serial No. 781,805

8 Claims. (Cl. 311—87)

1

This invention relates to improvements in folding card tables and the primary object is to provide an improved folding supporting structure for the table which will permit the table to be quickly and easily folded merely by releasing a latch near one edge of the table top and lifting at the same time. Thus the laborious individual release and folding of the four legs of the common table is completely done away with. The table is, of course, as readily unfolded and set up for use by a single operation and is automatically latched when it reaches position for use.

Another object of my invention is to provide a simple and easily operating folding structure of this kind which in addition has the very important advantage of providing rigid support for the table while it is in use, and which further supports the table at a plurality of widely spaced points to prevent both sagging and tilting of the table top.

These and more detailed and specific objects will be disclosed in the course of the following specification, reference being had to the accompanying drawings, in which—

Fig. 1 is a side elevation of my improved card table showing it in the operative position and with the table top shown in cross section.

Fig. 2 is a similar view but showing the table partially folded.

Fig. 3 is a bottom plane view of the table with the supporting structure unfolded as in Fig. 1.

Fig. 4 is a detailed sectional view along the line 4—4 in Fig. 3.

Referring now more particularly and by reference characters to the drawing, A designates generally a card table top which may be of any desired construction and which is here shown as comprising a top board 10 with a marginal depending rim 11 and with two parallel cross bars or cleats 12 extending across the underside of the top board. I do not, of course, limit myself to the particular table top here shown and by the use of suitable brackets or cleats, my supporting leg structure may be readily applied to any usual type of table.

My improved folding supporting structure for the table comprises a pair of leg units or frames designated generally and respectively at B and C, and a pair of corresponding brace link units or frames indicated generally at D and E. Each leg unit B and C comprises a pair of legs 13 and 14 which stand in inverted V-shaped positions when the table is in use, as seen in Fig. 1, and which further have their lower portions angled

2

outwardly as seen in Fig. 3 so that the bumper equipped lower ends 15 of the legs have the necessary wide bearing contacts with the floor. The upper ends of the legs 13 and 14 are flattened and interfitting as indicated at 16, and they are pivoted together upon a cross rod 17 which connects the legs of the respective pairs. It will be noted that the cross rod 17 has no pivotal or other engagement with the table top so that the upper ends of the legs are free to move with respect to the table top except for latching mechanisms later to be described. Wear plates 18 are secured to the cross bars 12, between which the pivoted upper ends of the leg units are positioned, and these wear plates extend out between the table top and the upper ends of the legs to prevent wearing contact between the legs and the top board 10. The legs 13—13 and 14—14 of the leg units B and C are rigidly connected intermediate their ends by cross braces 19 and it will thus be apparent that the leg units may fold and unfold in unison as will be presently described.

The brace link units D and E are X-shaped and each comprises crossed links 20 and 21, which are pivoted together where they cross as indicated at 22, and which are positioned alongside the leg units B (and C) to fold and unfold in planes parallel to said leg units. The lower ends of the links 20 and 21 are pivoted at 23 and 24 to the legs 13 and 14 and the upper ends of these links are pivoted at 25 and 26 to the inner sides of the cross bars 12. As seen in Fig. 3 the pivoted upper ends of the links 20 and 21 are suitably offset, as indicated at 27, to provide clearance for the legs. Link 21 is a broken link or comprises two sections 21^a and 21^b which are pivotally connected at their meeting ends at 28 and the upper sections 21^a of the links 21 are provided with downwardly opening notches 29 adapted in the unfolded position of the table to come to rest downwardly against a stop or pin 30 on the link 13. The links 20 have similar notches 31 adapted to similarly engage stops or pins 32 on the legs 14.

An actuating member or yoke, designated generally at 33, is provided and has diverging arms 34 which are pivoted at one end at 35 on the cross rod 17. The converging ends of the arms 34 meet a cross bar 36 which plays in a slot or guideway 37 formed between a latch bracket 38 and the underside of the top board 10. The latch bracket 38 is secured by its end feet 39 to the underside of the top board 10 adjacent one end of the table and a latch 40 is provided with sides 41 which loosely fit over opposite sides of

the latch bracket and are pivoted thereto by a pin 42. The latch sides 41 have projections 43 which normally engage the cross bar of the actuating member 33 and holding it at one end of the slot 37 as seen in Figs. 1, 3 and 4. A small spring 44 on the pin 42 normally urges the projections 43 into such position but by pushing upward upon the end 45 of the latch, it may be oscillated to move the projections clear of said cross bar 35, so it may move toward the table edge in the slot 37, as will be readily understood.

In the unfolded or operative position of the table as seen in Fig. 1 it will be apparent that the legs 13 and 14 will be braced apart by the crossed link units or frames D and E and will likewise be held against movement at their upper ends relative to the table by the actuating member 33 which is locked by the latch 40. To fold the table it is only necessary to lift upwardly momentarily on the end 45 of the latch so that its projections 43 clear the cross rod 36, and at the same time lift upwardly on this edge of the table, and the supporting structure will then fold as indicated in Fig. 2. In so doing the actuating member 33 moves toward the upper edge of the table while the links 21 of the link units break and fold upwardly and by a continuation of the movement, as indicated by the arrow in Fig. 2, the entire structure will fold flat against the underside of the table to a very compact condition. To again unfold the table and set it up for use, it is only necessary to pull its upper edge back in a downward direction and as the table top reaches its horizontal condition the supporting structure will be unfolded and automatically locked by the latch 40. It will thus be observed that the folding and unfolding of the table may be quickly carried out and certainly much more rapidly than the ordinary table wherein the four legs must be individually adjusted.

An important feature of my invention resides in the coaction of the notches 29 and 31 with the respective pins 30 and 32. These elements act as "half pivot" connections as the structure folds and unfolds and transmit load forces from the table directly through the upper parts of the links 20 and 21 to the legs 13 and 14 at these so that the combination of the inverted V-shaped leg frames and the X-shaped link frames form a series of triangular trusses or braces giving great rigidity to the table. It will further be noted that the table is supported at center points upon the upper ends of the leg units B and C and at four outspread points upon the upper ends of the links 20 and 21 at each side. Thus multi-point support against tilting and sagging of the table top is provided over a wide area.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. In a folding card table, a top and two pairs of supporting legs for the table, the individual legs of each pair being pivotally connected at their upper ends, a pair of crossed links for each pair of legs, the individual links of each pair being pivoted together where they cross and the links being pivoted at lower ends to the respective legs and at their upper end to the table top, a corresponding link of each pair comprising sections pivotally connected together for folding movements, a yoke member connected to the

upper ends of the legs and extending beneath the table top toward one edge, and a catch adjacent said edge for releasably engaging and latching the yoke members to thereby hold the pivoted ends to the legs against movements.

2. In a folding card table, the combination comprising a top, a pair of legs pivotally connected at their upper ends for folding movements, a pair of crossed links pivotally connected where they cross and pivotally connected at their lower ends to the respective legs and pivotally connected at their upper ends to the table top for folding movements in planes parallel to the legs, one of said links having two pivotally connected sections whereby it may fold upwardly, a member connected to the pivoted upper ends of the legs, and a latch for securing the member to the top to hold the upper ends of the legs against movement with respect to the top and thereby releasably lock the leg and link structures against folding movements.

3. In a folding card table, the combination comprising a top, a pair of legs pivotally connected at their upper ends for folding movements, a pair of crossed links pivotally connected where they cross and pivotally connected at their lower ends to the respective legs and pivotally connected at their upper ends to the table top for folding movements in planes parallel to the legs, one of said links having two pivotally connected sections whereby it may fold upwardly and permit the entire leg and link structure to fold flat against the underside of the top, and means for releasably locking the pivoted upper ends of the legs to the top to hold the leg and link structure against folding movements.

4. In a folding support structure for a card table top, the combination comprising a pair of inverted V-shaped leg units and a pair of X-shaped brace link units for each leg unit, each leg unit comprising two legs foldably connected together at their upper ends but movable with respect to the table top, the brace link units each comprising two crossed links pivoted where they cross and pivotally connected at the upper and lower ends respectively to the table top and the legs, and a corresponding link of each link unit comprising two sections connected end to end for upward folding movements.

5. In a folding support structure for a card table top, the combination comprising a pair of inverted V-shaped leg units and a pair of X-shaped brace link units for each leg unit, each leg unit comprising two legs foldably connected together at their upper ends but movable with respect to the table top, the brace link units each comprising two crossed links pivoted where they cross and pivotally connected at the upper and lower ends respectively to the table top and the legs, a corresponding link of each link unit comprising two sections connected end to end for upward folding movements, a member connected to the upper ends of the leg units and positioned underneath the table top, and a latch for engaging said member to releasably lock the upper ends of the legs to the table top while the table is in use.

6. A folding supporting means for one side of a card table top, comprising, in combination, a pair of upwardly converging legs pivotally connected at their upper ends, a pair of crossed links pivotally connected where they cross and located alongside the legs with their pivot connection below the leg pivots, the said links at their lower ends being pivoted to the legs and at their upper ends pivoted to the table top, one of said links

having two pivotally connected and upwardly foldable sections, and upwardly releasable supporting connections between the links and legs at the points where the links cross the legs.

7. A folding supporting means for one side of a card table top, comprising, in combination, a pair of upwardly converging legs pivotally connected at their upper ends, a pair of crossed links pivotally connected where they cross and located alongside the legs with their pivot connection below the leg pivots, the said links at their lower ends being pivoted to the legs and at their upper ends pivoted to the table top, one of said links having two pivotally connected and upwardly foldable sections, and the said links diverging from their pivot connection and crossing the upwardly converging legs, the links having downwardly opening notches where they cross the legs, and stop means on the legs for engagement with said notches to transmit downward forces from the table top along the links to the legs at these points.

8. A folding supporting means for one side of a card table top, comprising, in combination, a pair of upwardly converging legs pivotally connected at their upper ends, a pair of crossed links pivot-
